UNITED STATES PATENT OFFICE.

ALBERT J. REDEMSKI, OF CHICAGO, ILLINOIS, ASSIGNOR TO ATLAS BOX COMPANY, OF CHICAGO, ILLINOIS, A CORPORATION OF ILLINOIS.

FIBER-BOARD PACKAGE.

Application filed August 4, 1926. Serial No. 126,982.

This invention relates to improvements in fiber board packages and more particularly to packages for liquid products, such as are ordinarily sealed in cans.

5 The object of the invention is to provide a package which can be more readily handled in shipment and by the user, by the provision of hand-holes in the sides and near one end thereof. Such a package 10 is especially designed for relatively heavy and cumbersome products, such as large cans of oil, chemicals, syrups and the like.

For convenience of disclosure, I have shown a package for the ordinary 5-gallon 15 can or drum of oil, this being a good example of a package which is exceedingly difficult to handle when enclosed in the usual case without handles.

In the accompanying drawings, 20 Figure 1 is a perspective view of a sealed package embodying the invention.

Figure 2 is a perspective view of the fiber container open and the contents removed.

Figure 3 is a perspective view showing 25 the outer container open and the insert removed.

Figure 4 is a view in vertical section through the package as taken on line 4-4 of Figure 1.

30 Figure 5 is a perspective view in elevation of the insert for the upper part of the outer container.

Figure 6 is a view in elevation of the blank from which the insert shown in Figure 5 is formed.

35 Figure 7 is a perspective view of a modified form of insert.

Figure 8 is a view in elevation of the blank from which the insert shown in Figure 7 is made.

40 Figure 9 is a view in vertical section through the package showing the insert of Figures 7 and 8 in place.

Figure 10 is a perspective view of another 45 modified form of insert.

Figure 11 is a view in vertical section through the package showing the insert of Figure 10 in place.

The outer container 1 is of the usual fiber 50 board carton construction consisting of side walls 1^a and end walls consisting of four flaps 1^b connected with each of the side walls and overlapping each other in pairs, with the flaps of each pair abutting at their 55 forward edges. The end flaps are prefer-

ably sealed by strips 2 of adhesive paper tape, as shown in Figure 1.

Fitting within the outer container is a can or tin container, such as ordinarily used for lubricating oils and having a spout 60 3^a and a ring handle 3^b on its top wall.

The height of the outer container is somewhat greater than that of the inner container, thus providing a space of from three 65 to four inches between the top of the can and the top wall of the outer container.

Within this space is placed an insert 4, the same being a hollow box-like member (Figure 5) adapted to fit snugly within 70 this open space. The insert is preferably made from the same material and fills the space above the top of the inner container

3. In its blank form (Figure 6) the insert consists of rectangular sections with dividing score lines so that when the blank 75 is folded and stapled, as at 4^a, it forms a rigid box with top, bottom and side walls. In two of the opposing side walls of the insert are formed longitudinal slots or hand-holes 4^b, 4^c, and at one corner of what would 80 be the bottom wall, is a circular hole 4^e. As constructed from the blank shown in Figure 6, one pair of side walls would be of double-thickness of the material and the other side walls of but a single thickness. 85 The hand-holes 4^b are preferably cut in the walls of single thickness.

In the corresponding positions in opposite side walls of the outer container 1 and near the top thereof, are hand-holes 5-5. 90 Thus when the insert is fitted into the top space of the container, it is so done that the pairs of hand-holes register with each other, thus forming single hand-holes on opposite sides of the package, as shown in 95 Figures 1 and 4. The circular opening 4^e at the corner of the bottom wall of the insert, receives the spout 3^a of the inner container 3.

In this manner the package is provided with the equivalent of handles, so that it 100 can be conveniently handled in shipment or otherwise prior to the removal of the inner container.

Figures 7 and 8 disclose a modified construction for a fiber-board insert, in which considerably less material is used, and although not affording as rigid a construction is calculated to be quite as satisfactory for ordinary uses. This insert 6 consists 105 of a single central panel 6^a having marginal 110

flaps 6^b which are folded at right angles to form the side walls. In opposite side walls are formed the hand-holes 6^c as before, and at one corner of the center section is the 5 same circular opening 6^d. It is preferable that this insert 6 be placed in the top of the container with the central section downward, as shown in Figure 9, with the edges of the side walls abutting against the top 10 end wall of the outer container, thus avoiding the possibility of the flaps being forced between the sides of the inner and outer containers, which might occur if the position of the insert were reversed.

15 In Figures 10 and 11 is shown a further modification for the insert, which consists merely of an open rectangular frame 7 of wood pieces nailed together at their ends, and a pair of recesses 7^a cut or hollowed 20 out of the pieces on opposite sides of the frame, and this frame is fitted in place as in the case of the other inserts, with the recesses 7^a registering with the hand-holes in the outer container, as shown in Figure 25 11. The recesses could be cut through to form slotted hand-holes, as in the case of the fiber board inserts, although the recessing of the wood is a less expensive process than slotting, and hence is preferable for that 30 reason.

Having set forth the construction and advantages of a container for packaging goods of the particular variety herein disclosed, I claim as my invention:

35 1. A package for canned products comprising a metal container, a carton adapted to receive said container with a substantial space between the top of said container and

the top of said carton, and an insert fitting in said space and having walls extending 40 transversely thereof between said container and the opposite wall of said carton, said insert having a hand hole in one of its walls and adapted to register with a complementary hand hole in said carton.

2. A package for canned products comprising a metal container, a carton adapted to receive said container and of increased dimension in one direction to provide a substantial space between one side of said container and the corresponding wall of said carton, and an insert adapted to fit snugly 50 in said space and comprising walls engaging flatwise against the wall of said carton surrounding said space, said insert and carton 55 having registering hand holes formed in the walls thereof and opening into said space.

3. A package for canned products comprising a contents container, a carton adapted to enclose said container and having flaps 60 at one end, said carton being of increased dimension in one direction to provide a space of substantial height between the top of said container and the flap closed end of said container, and an insert adapted to fit 65 within said space and comprising walls extending transversely thereof and bearing edgewise against the top of said container, there being formed hand holes in said walls of the insert adapted to register with hand 70 holes in walls of said carton and opening into said space.

Signed at Chicago, Ill., this 31st day of July, 1926.

ALBERT J. REDEMSKI.
